UNITED STATES PATENT OFFICE

2,419,779

SNOW EXCAVATOR

Norman L. James, Ingersoll, Ontario, Canada

Application October 23, 1944, Serial No. 560,055
In Canada November 3, 1943

5 Claims. (Cl. 37—43)

1

This invention relates to improvements in devices for excavating snow and ice from highways, railways and airport landing fields, and the principal objects of the invention are to provide a machine of strong and durable construction which may be attached to a truck, tractor or locomotive, which will effectively cut into deep snow or surface-packed ice and deliver it in loose form progressively as the machine advances to a high speed ejecting unit which delivers the snow or ice clear of the path cut by the machine.

The principal feature of the invention consists in the novel construction and arrangement of a horizontal revolving member extending transversely of the machine having helical blades adapted to engage and cut into the snow and directing same to a coaxially arranged member rotated at a considerably higher speed than the rotation of the cutting member, said high speed member delivering the snow and ice to a delivery chute.

In the accompanying drawings

Figure 1 is a plan view of a machine constructed in accordance with this invention having the delivery chute arranged at one end thereof.

Figure 2 is a longitudinal and vertical sectional elevation of the machine shown in Figure 1 taken on the line 2—2.

Figure 3 is a plan view of a modified form of the machine having the delivery chute arranged centrally of its length.

Figure 4 is a front elevational view of the machine shown in Figure 3.

Figure 5 is an end elevational view of the machine illustrated in Figures 3 and 4.

Figure 6 is a part longitudinal sectional detail of the structure illustrated in Figure 3.

Figure 7 is an end elevational view in part section showing a slightly modified detail in the driving mechanism of part of the machine.

Figure 8 is an enlarged sectional detail of the driving gear connection between the main longitudinal shaft and the slow-speed spiral cutting member.

Figure 9 is an end or face view of the structure illustrated in Figure 8, being a section on the line 9—9 of Figure 8.

Many different types of snow plows or excavators have been proposed in which horizontally arranged spiral cutting members are rotated to engage and cut away the packed snow on highways or other areas, and these spiral cutting members are, in numerous forms of machines proposed, arranged to deliver the snow to fan

2

blades either integral with the spiral cutters or arranged adjacent thereto.

In machines of this type it is highly desirable that the snow and ice as it is cut away from the banks and drifts or road surfaces be passed continuously to the delivery means so that packing or jamming will not take place, and it is important that the broken-up material be removed from the delivery ends of the spiral cutters with such speed as will prevent clogging.

The present invention has been devised particularly with this latter result in view, and this objective is achieved by the arrangement of a delivery fan co-axial with the spiral cutters operating at a higher speed of revolution than that of the cutters.

On reference to the accompanying drawings the form of the invention illustrated in Figures 1, 2 and 7 comprises a casing 1 which is suitably supported in front of a truck or tractor 2, or other motive vehicle. This casing is formed with vertical end plates 3 and 4, and journal blocks 5 and 6 are secured to these end plates respectively, in alignment one with the other.

25 A shaft 7 rotatably mounted in the journal blocks 5 and 6 extends from end-to-end of the machine, one end thereof projecting through the block 5 and having mounted thereon a suitable gear or sprocket wheel 8.

30 A jack shaft 9 is horizontally journalled in suitable bearings supported from the casing 1 in a horizontal position substantially vertically over the shaft 7, and carries a sprocket wheel 10 which is connected by a suitable chain with the sprocket 8.

35 The jack shaft 9 is driven through a pair of intermeshing bevel pinions 11 driven by a shaft 12 which is connected to a suitable source of power preferably carried by the truck or tractor device 2.

40 A fan member formed with a central drum 13 and radial blades 14 is mounted on the shaft 7 inside the plate 3, and the blades operate within a part-circular housing which opens to a discharge chute 15. The fan is rigidly secured to the shaft and rotates therewith.

45 Rotatably mounted on the shaft 7 adjacent to the fan member 13 is a spider 16 which supports the smaller end of a tubular frusto-conical member 17, and a similar spider 18, of larger radius than the spider 16, is mounted on a bearing block 19 rotatably mounted adjacent to the other end of the shaft, said spider supporting the larger end of the frusto-conical tube 17.

50 Spiral cutting flanges 20 extend rigidly from the member 17 from end-to-end. These are

preferably of uniform external diameter and operate within a part-cylindrical wall 21 of the casing 1 which extends along the back and topside of the rotary member.

The bearing block 19 is formed with a circular flange 22. A flange plate 23 of corresponding diameter to the flange plate 22 is formed with a bearing boss 24 which is rotatably mounted on the outer periphery of the bearing block 6 in which the shaft 7 is mounted.

The flange plate 23 and flange 22 are connected together by a pair of spindles 25 arranged diametrically opposite to each other, and spur gears 26 are rotatably mounted on each of these spindles to mesh with a spur pinion 27 keyed to the shaft 7.

Spur gears 28, preferably of smaller diameter than the gears 26, are rotatably mounted on the spindles 25 and mesh with an internal gear ring 29 which is rigidly secured to the end plate 4 of the casing.

It will be understood that upon the rotation of the shaft 7 the pinion 27, which is keyed thereto, rotates, and it imparts rotation to the gears 26. The gears 26 and 28 are keyed to the spindles 25, consequently rotation imparted to the gears 26 rotates the gears 28, and these meshing with the fixed gear rings 29 are caused to travel around said gear ring, thereby carrying the flange plates 22 and 23 with a rotative movement, the speed of which is reduced through the train of gears described, and the frusto-conical member 17 carried by the spider mounted on the hub of the flange member 19, is rotated so that the spiral cutting flanges are rotated to engage the surface of snow to be removed. These spiral flanges may be provided with suitable cutting teeth to cut into hard crusts of snow or ice as may be desired.

It will be understood that the shaft 7, upon which the discharge fan 13-14 is mounted, operates at a relatively high speed of rotation to the speed or rotation of the spiral flange cutting member, and as the snow is cut and is fed longitudinally toward the fan by the rotative movement of the frusto-conical member, the snow being forced longitudinally between the spiral flanges is taken as it emerges into the path of the fan blades and carried around at high speed and thrown through the discharge opening 15.

The discharge may be provided with any suitable form of chute or guide for directing the flow of snow into transport vehicles or to be thrown clear of the path cut by the excavating device.

It will be noted on reference to Figures 1 and 7 that the end plate 3 is carried forwardly to a greater distance than the end plate 4, and an angled vertical face plate 30 extends inwardly therefrom and forms a cutting edge to cut into a snow bank and thus enable a clear-cut boundary to be made at the inner operating end of the machine carrying the delivery fan.

Arranged within the forward extension of the casing formed by the end plate 3 and the angle plate 30 is a vertical shaft 31 mounted in suitable bearings at the top and bottom, and on the bottom end of this shaft is arranged a horizontal cutter member 32 which operates close to the road surface to cut and break up caked snow or ice formations. The shaft 31 is driven through bevel gears 33 operated by a shaft 34 driven through a worm gear 35 operated by a worm 36 carried by the jack shaft 9.

It will be noted from the construction described that this ice-cutting member, together

with the spiral snow cutter and feed member and the high-speed delivery fan, are all operated from a single operating connection leading from the source of power.

5 The structure is therefore extremely simple and is of a rugged construction which will stand extraordinary abuse.

In the form of the invention illustrated in Figures 3, 4 and 6, the main casing of the machine, 10 with its longitudinal shaft and drive connections, are substantially the same, but the fan casing 31 is located substantially midway of the length of the machine and the fan 38 is rigidly mounted on the shaft within said casing.

15 Frusto-conical spiral flanged members 39 and 40 are rotatably mounted on the main shaft at either side of the fan casing and both feed inwardly to said fan casing. These frusto-conical members are driven at a reduced speed from the speed applied to the fan by an arrangement of gearing at the outward end of each of the frusto-conical members, similar to that described and shown in detail as arranged at the larger end of the single frusto-conical member illustrated in Figures 1 and 2.

20 An ice-cutting member 41, similar to the cutter 32, is mounted in the lower portion of a V-shaped extension 42 of the fan casing. This cutter is driven by a vertical shaft 43, shown in Figure 5 in dotted lines as being connected with a worm drive operating from the jack shaft 9 through an angle shaft 44.

25 A straight bevel gear drive similar to that shown in Figure 7 may be used for this ice cutter if desired.

30 What I claim as my invention is:

1. In a snow excavator, in combination, a part cylindrical casing having rigid closed ends and a discharge chute, journal bearings mounted centrally of said cylinder ends, a shaft journaled in said bearings, a fan member secured on said shaft opposite said discharge chute, a spider rotatably mounted on said shaft adjacent to said fan, a spider rotatably mounted on said shaft adjacent to a closed end of the casing, a tubular member supported on said spiders having spiral cutting flanges extending from its periphery and discharging into said fan, means for rotating said shaft, and a reduction gear enclosed within the outward end of said tubular member and driven by said shaft and driving said spiders and tubular member at a slower speed than said shaft.

2. A device as claimed in claim 1 in which the spider remote from the fan and enclosed within the tubular member is mounted on the hub of a flange plate rotatably mounted on the shaft, a flange plate being rotatably mounted on the exterior of the shaft journal on the cylinder end plate, a gear ring being mounted on the inner side of the end plate, gear wheels supported between said flange plates to mesh with said gear ring, and a pinion secured to the shaft.

3. In a snow excavator, in combination, a part cylindrical casing having rigid closed ends and a discharge chute, journal bearings mounted centrally of said cylinder ends, a shaft journaled in said bearings, a fan member secured on said shaft opposite said discharge chute and having a central drum, spiders rotatably mounted on said shaft, a tubular member supported on said spiders having one end thereof overlapping the adjacent end of the drum and having spiral cutting flanges extending from its periphery and

discharging between the blades of said fan over the periphery of said fan drum, means for rotating the shaft, and means driven by the shaft for rotating said spiders and the flanged tubular member at a speed lower than the speed of the fan.

4. In a snow excavator, in combination, a part cylindrical casing having rigid closed ends and a discharge chute, journal bearings mounted centrally of said cylinder ends, a shaft journalled in said bearings, a fan member secured on said shaft opposite said discharge chute, a frusto-conical tubular member separate from said fan and extending outwardly therefrom co-axially with said shaft, means for rotatably supporting said frusto-conical tube from said shaft, means for rotating said shaft, and means enclosed within said frusto-conical tube for rotating same at a lesser speed than said shaft.

5. In a snow excavator, a part cylindrical fan casing having a horizontal axis, a fan within said casing, a casing extending laterally from said fan casing, means within said extension casing for feeding snow to said fan, a driving gear for

said fan and feeding means arranged above said casing, a vertical shaft mounted in said fan casing forward of the fan and operatively connected to said driving gear, and a horizontal rotary cutter mounted on the lower end of said vertical shaft below the bottom of the fan casing to clear ice and snow from in front of the fan casing as the excavator is advanced.
